UNITED STATES PATENT OFFICE.

REINHARD T. TORKELSON, OF WORCESTER, MASSACHUSETTS, ASSIGNOR TO FRED IVER JOHNSON, OF FITCHBURG, MASSACHUSETTS.

SPOKE-CLAMP FOR NON-SKID CHAINS.

1,304,122.

Specification of Letters Patent.

Patented May 20, 1919.

Application filed March 12, 1919. Serial No. 282,129.

To all whom it may concern:

Be it known that I, REINHARD T. TORKELSON, a citizen of the United States, residing at Worcester, in the county of Worcester and State of Massachusetts, have invented a new and useful Spoke-Clamp for Non-Skid Chains, of which the following is a specification.

The object of this invention is to provide 10 a new and improved spoke clamp for non-skid chains, which can be very readily applied in position and which can be very easily adjusted.

The invention is shown in the accompanying two sheets of drawings, in which—

Figure 1 is a cross sectional elevation of part of the rim of a wheel showing one of my clamps in place on the spoke;

Fig. 2 is a section taken on the line 2—2 20 of Fig. 1;

Fig. 3 is an end elevation;

Fig. 4 is a view similar to Fig. 2 illustrating a different way the clamp may be applied in position;

Fig. 5 is an end elevation, and

Fig. 6 is a bottom view of one of the corner pieces;

Fig. 7 is an end elevation, and

Fig. 8 is a bottom view of one of the 30 grooved washers;

Fig. 9 is a detail of the clamping bolt;

Fig. 10 is a view similar to Fig. 2 illustrating a modification;

Fig. 11 is a side elevation of said modification, and

Fig. 12 is an end elevation of said modification.

It is customary on heavy wheels, such as are employed on trucks, to use a number of 40 non-skid chains, say six or seven in number, attached at their ends to the spokes of the wheel.

My invention relates particularly to an improved spoke clamp to which the ends of 45 one of the non-skid chains can be attached.

The device consists essentially of four corner pieces preferably grooved, two U-shaped clamp bars, and clamping means such as bolts and nuts, the parts being arranged so that when the clamp is placed in 50 position, the U-shaped clamp bars can be adjusted in and out on the clamp, and the

clamp can be adjusted up and down on the spoke and the parts rigidly held in adjusted position by tightening the nuts. 55

Referring to the drawings and in detail, A designates one of the four corner pieces, the same being somewhat F-shaped in cross section and having two grooves $a-a$ across its back face and having a hole a' there- 60 through.

B designates one of the U-shaped clamp bars. These preferably are made out of heavy wire bent to assume the shape shown.

In the plan shown in the first eight figures 65 of the drawings, the corner pieces are arranged to come next to the spoke and the clamp bars are arranged outside of the same. The clamping means provided in this plan consists of four washers C having grooves 70 $c-c$, bolts D having shoulders d square in cross section near their heads, and nuts E.

The clamp is placed in position on the spoke, as shown in the drawings. With the nuts lightly adjusted, the clamp bars B are 75 pushed in or pulled out to come at any desired relation relatively to the rim of the wheel, and the clamp is adjusted up and down on the spoke to tighten the chain as much as desired. When the clamp is in the 80 desired adjusted position, the same is rigidly held in position simply by tightening the nuts.

The clamp may be applied so that the clamp bars come at right angles to the plane 85 of the wheel as illustrated in Fig. 2, or so that they may stand parallel therewith as illustrated in Fig. 4.

In placing the parts in position on the spoke, they are preferably arranged so that 90 the nuts will come on the same side thereof for convenience.

In the modification shown in Figs. 10, 11 and 12, the corner pieces A' have the grooves a^2-a^2 on their inner sides, and the 95 clamp bars B fit in these grooves. The holes a^3-a^3 in the corner pieces are made square or oblong in shape, as shown in Fig. 11 where the head of one of the bolts is indicated as removed.

This modified clamp is applied and adjusted in the same manner as the previously described structure. This last described form of the device is somewhat cheaper to 100

manufacture and is better adapted for some locations, as the four grooved washers are not needed.

The details and arrangements herein shown and described may be greatly varied by a skilled mechanic without departing from the scope of my invention as expressed in the claims.

Having thus fully described my invention, what I claim is—

1. A clamp for non-skid chains, consisting of corner pieces, two U-shaped clamp bars, and means for clamping these parts on the spoke of a wheel.
2. A clamp for non-skid chains, consisting of four grooved corner pieces, two U-shaped clamp bars engaged thereby, and means for clamping the parts in position on the spoke of a wheel.
3. A clamp for non-skid chains, consisting of four grooved corner pieces, two U-shaped clamp bars fitted thereto, two bolts extending through the corner pieces, and nuts carried by said bolts, whereby said nuts

will act to clamp the corner pieces in position on the spoke of a wheel and the U-shaped clamp bars rigidly to the corner pieces.

4. A clamp for non-skid chains, consisting of four grooved corner pieces, two U-shaped clamp bars, four grooved washers, and two bolts fitting through the parts and having nuts for securing the clamp in adjusted position on the spoke of a wheel.

5. A clamp for non-skid chains, consisting of four grooved corner pieces, two U-shaped clamp bars, four grooved washers with square holes through the same, two bolts with square sectioned shoulders under their heads, and two nuts, the parts being arranged so that by tightening the nuts the clamp bars will be rigidly secured to the corner pieces and the clamp will be held in adjusted position on the spoke of a wheel.

In testimony whereof I have hereunto affixed my signature.

REINHARD T. TORKELSON.
